FIG. 5

FIG. 6

FIG. 7

Figures 1, 2, 3 and 4 are plan views of portions of the complete repeating unit of my new design. Figure 1 joined to Figure 2 at the broken lines on the right side of Figure 1 and the left side of Figure 2 represents the left half portion of one complete unit of the new design and a portion of the adjacent repeating unit. Figure 3 joined to Figure 4 at the broken lines on the right side of Figure 3 and the left side of Figure 4 represents the right half portion of one complete unit of the new design and a portion of the adjacent repeating unit. Figure 5 is a plan view of an enlargement of a portion of Figure 1. Figure 6 is a plan view of an enlargement of a portion of Figure 5. Figure 7 is a cross sectional view taken on line 7-7 of Figure 6.

I claim:

The ornamental design for a plastic sheet material, substantially as shown and described.
